UNITED STATES PATENT OFFICE

JOSEPH LEVOTCH, OF CAMDEN, NEW JERSEY

SHOE UPPER AND METHOD OF CUTTING THE SAME

Application filed March 11, 1931. Serial No. 521,651.

My invention relates to new and useful improvements in shoe uppers and the method of cutting the same and has for one of its objects to provide a device of this character which will be simple in construction, inexpensive in the cost of manufacture and which may be assembled in an article of footwear with less likelihood of damage during the process of manufacturing the article of footwear, therefore seldom requiring the making of repairs.

Another object of the invention is to provide a shoe upper fashioned by the method to be herein described which will be more comfortable to the wearer and have a more pleasing appearance principally because the upper is not wrinkled and the shoe will not become crooked during the time it is worn.

A further object of the invention is to so fashion the shoe upper that it may be readily attached to the bottom or sole of the shoe without wrinkling, thereby eliminating the ironing operations and the consequent possible damage to the leather and the waste of time for such ironing operations.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:—

Fig. 1 is a plan view of a bottom or sole of a shoe that was generally made years ago and to some extent is still manufactured today.

Fig. 2 is an enlarged face view or plan of a portion of a shoe upper or the pattern of a shoe upper used particularly in the manufacture of a slipper and showing both sides of the vamp and the quarters to be alike suitable for use in connection with a shoe bottom or sole illustrated in Fig. 1, and generally used at the present time in the manufacture of articles of footwear having a bottom or

sole of different shape from that illustrated in Fig. 1.

Fig. 3 is a view similar to Fig. 2 folded on its median line.

Fig. 4 is a view similar to Fig. 1, illustrating the shape or configuration of the present-day bottom or sole of an article of footwear.

Fig. 5 is an enlarged plan or face view of a portion of a shoe upper, the same being co the combined vamp and quarters or a blank or pattern of the same when constructed in accordance with my invention.

Fig. 6 is a vamp only of that part of the shoe upper illustrated in Fig. 5 folded along its median line.

Fig. 7 is a view of the quarters or the blank or pattern thereof folded or super-imposed one on top of the other, the outer one being on the top.

Fig. 8 is a similar view with the quarters positioned so that their bottom edges are coincident with each other.

Fig. 9 is a view of the article illustrated in Fig. 3 folded along its median line.

Fig. 10 is a side elevation of the complete upper of a high shoe utilizing the elements and method of my invention for the construction thereof.

Fig. 11 is a view of the top quarters with the outer top quarter super-imposed on the inner one.

Fig. 12 is a view of the parts of a boot upper folded or super-imposed one upon the other.

Years ago or formerly, the bottoms or soles of shoes were fashioned on what might be termed symmetrical lines. In other words, both halves of the bottoms or soles were equal and as shown in Fig. 1, the line *a, c, e, b* is the same length as the line *a, d, f, b* and therefore the line *a, b* divides the bottom or sole into two equal halves. The line *c, d* divides the ball of the sole, marked *B*, from the shank, marked *S*, while the line *e, f* divides the shank from the heel, marked *H*. A line *g, h* is located on the transverse center of the shank and further shows the equality of the several parts of the shoe bottom or sole because the parts above this line on either side of the line

70

75

85

90

95

100

a, b are equal to each other while the parts below the line *g, h* on either side of the line *a, b* are also equal to each other.

To fit such a shoe bottom or sole, an upper 5 of an article of footwear was produced to coincide therewith and a portion of such an upper is illustrated in Figs. 2 and 3 wherein 10 15 represents a vamp while 16 and 17 represent the lower quarters formed as an integral 15 article or sewn or otherwise connected therewith and where the quarters are separate from the vamp they may be produced from a single piece of material or connected along the contiguous or meeting edges falling on the median line *i, k*. A line *n, o* drawn through the rear corners of the vamp 15 will be at right angles to the line *i, k*, and a line *i, l*, drawn from the toe to one of the corners will form a triangle *i, l, k* equal to the triangle 20 *i, m, k* when the line *i, m* is drawn from the toe to the other corner and this will become particularly apparent by reference to Fig. 3 which shows the upper or the portion of the upper illustrated in Fig. 2 folded on the line *i, k*.

Such uppers of symmetrical design or equal measurements are at the present time used for slippers, half-shoes, shoes and boots.

This symmetrical or equal arrangement 30 of the shoe upper is impractical because the human foot is not the same on both sides of the longitudinal center or median line. Furthermore, the modern last is built to more closely resemble the shape of the human foot 35 and the symmetrical or equally constructed upper, although still manufactured, does not fit said modern last and shoes made thereon are not well fitted nor comfortable.

Fig. 4, illustrates the bottom or sole of a 40 shoe constructed for use in connection with the modern last which is most widely used at the present time. This bottom or sole shows inequality of measurement. The center line *a', b'* which runs from the middle of the toe to the middle of the heel does not divide the bottom into equal halves. A line *a', p* which runs from the middle of the toe to the outside of the heel divides the ball of the bottom into substantially equal 45 halves but said line *a', p* does not lie in a straight direction to the heel and a line *q, b'* which does pass through the middle of the heel runs to the outside of the toe and while it divides the heel into two substantially equal 50 halves is considerably to one side of the center line of the ball of the bottom or sole.

Like in the illustration in Fig. 1 the line *c', d'* and *e', f'* divide the ball of the sole from the shank and the latter from the heel 55 respectively and the arrangement and location of these lines plainly illustrates that the inner part of the shank is longer than the outer part and the line *g', h'* which divides the shank into two parts lies in the exact center of the outer side of the shank but is

not in the exact center of the inner side of the shank although the distance from *g'* to *b'* is exactly the same as the distance from *b'* to *h'* and it is the line *g', h'* the foundation on which shoes of correct measurement can be made.

If measurements of the edges of the bottom or sole of the shoe shown in Fig. 4 are taken without consideration of the convex portions of said edges, it will be found that 75 the distance from the middle of the toe at *a'* to the middle of the heel at *b'* around the inner edge, relative to the shoe on the foot, is shorter than the distance around the outer edge or part. The chamfer of the arch at 80 the inner and outer edges of the shank play no extra part in the length of the measurement of the foot nor in the modern last in shoe making.

The old style last, the general shape of 85 which is illustrated in Fig. 1 when compared with the modern last, the general shape of which is illustrated in Fig. 4 shows a very marked difference and my invention is made on exact measurement of the foot and the 90 modern last.

In Fig. 5 I have illustrated the upper 18 cut to the modern last illustrated in Fig. 4, from examination of which it will be immediately obvious that the lower rear corners 95 19 and 20 are not even and the one numbered 19, which is the lower inside rear corner, is shorter than the one numbered 20, which is the lower outside rear corner, as indicated by the line *l', m'*. The top corners 21 100 and 22 are just the opposite of the bottom or lower corners 19 and 20 because the corner 22 extends outside of the line *l', m'* while the corner 21 is inside of the foot and the modern last on the top from the inside of the foot 105 is longer than the top line from the outside.

The line *n', o'* in Fig. 5 indicates that the rear end of the vamp 23 on the inside of the article of footwear is shorter than the rear end of said vamp at the outside to the same 110 extent as there is a difference between the distances from *i'* to *l'* and *i'* to *m'* because the lines *n', o'* and *l', m'* are parallel but not at right angles to the center line *i', k'*.

The shape and arrangement of that part of 115 the upper including the vamp 23 and the lower quarters 24 and 25 is such that it corresponds with the shape and measurement of the human foot and the present-day last neither of which is even on both sides. This 120 being true, the upper must be cut in the manner illustrated herein to properly fit the foot and the modern last and only by following the measurement and design set forth herein can shoes of the finest and most exact fit be 125 made.

In Fig. 6, the vamp 23 which is illustrated in Fig. 5 is shown folded along its center line and plainly illustrates the differences between the two halves thereof, the half that is 130

on the inside of an article of footwear is represented by the numeral 26 while the half that occupies the outside of the shoe is represented by the numeral 27.

5 In Fig. 7, the lower quarters 24 and 25 are illustrated super-imposed one on the other with the throats 28 and 29 co-inciding with each other and shows that when so positioned, the main or body portions thereof do not co-
10 incide and if said quarters are moved until their lower edges co-incide, as illustrated in Fig. 8, then the throats are moved apart, the throat of the outer quarter assuming a position a considerable distance forward of the
15 throat of the inner quarter.

In Fig. 9, the complete upper is represented as folded before the sewing together of the back and inner and outer parts of the quarters. It can clearly be seen that the back, in-
20 ner and outer parts are not even or do not co-
incide with each other and when sewn to-
gether the whole upper will have a crooked
25 appearance, but the points n' and o' will assume positions directly opposite each other and the upper will then exactly fit the last.

The upper so far described is particularly adapted for use in a low shoe or slipper and while the upper for a high shoe should be cut on the same principle as that for a low
30 shoe, there is a difference but this difference is only that the top quarters 30 and 31, Figs. 10 and 11, must be cut according to or to correspond with the bottom quarters 24' and the inner back part of the top quarter on the bot-
35 tom must be that much wider than the bottom inner quarter as the top is longer as is shown by Fig. 9 the backward top corner 21.

The high shoe just as the low shoe must be cut to the measurement of my invention, and
40 can be made in any style and design. It also can be made with separate vamp and quarters or with the vamp and quarters in one piece in which case the top line of the upper will coincide with the broken line r, s , in Fig. 10,
45 and the solid lines emerging therewith except the full quarters, which are cut in one piece, from the top to the bottom, because this style of full quarter cannot be fitted to this system of measurement.

50 In Fig. 11, the inside and outside top quarters 31 and 30 are illustrated with the outside top quarter superimposed on the inside top quarter.

In Fig. 12, is illustrated a high boot and
55 when a one-piece legging is cut, it must be folded together as shown in Fig. 12, according to the last, as the inner top line illustrates that the inside bootlegging 32 must be wider than the outside portion of the boot-
60 legging 33.

The throat 34 could then be cut which will give the correct measurement along the lines t, u and v, w . According to the leggings,
65 the vamp must be cut to the measurement shown by Fig. 6, the outside of the vamp be-

ing longer than the inside thereof. The quarters of the boots 35 and 36 must be cut along the same principle as illustrated by Figs. 7 and 8. However, the legging parts must be sown together before the quarters are fitted to them; the quarters must be sewn together from the back before they can be fitted to the bootlegging.

To cut and to fit uppers to equal measurement as is done today is a little easier, but to make the shoe from these uppers is very difficult for the workers. It also creates considerable trouble for the shoe manufacturer because the equally measured upper does not fit the modern last and consequently causes much damage. Therefore, many shoes have to be repaired before they can be disposed of. A great deal of money and time are needlessly wasted in making shoes from equally measured uppers. Hence the customer does not get much satisfaction from this kind of footwear.

To the measurements of my invention can be made boots, half-shoes, high shoes, slippers, sandals, etc., nail-soled shoes, welt and turned shoes or others of any type in any and all sizes and widths, any kind of cut and design and from skin, cloth or other suitable material.

The advantages of using this system of measurement is as follows:

Easier manufacturing; easier making; less damage incurred, therefore seldom requiring repairing; costs less; more comfortable to the wearer; and having a more pleasing appearance. On the whole they have a much greater value.

The shoe will not become crooked during the time it is worn because the lines i', k' and n', o' assume their proper positions without forcing.

By the use of my method of measurement:—1. During the time the shoe is made there is no trouble with wrinkles, especially in turned work, therefore no time is wasted in ironing to make the skin smooth and the possible consequent burning is eliminated. 2. It is easier to set the heels, especially wooden heels on women's shoes. 3. It is very easy to set the heels on women's turned shoes because the heel seat is smooth and straight without any ridges or lumps as the points n' and o' , 11 and 20, 21 and 22 will be exactly opposite each other. 4. There will be no sack-like wrinkles around the heels in satin or any other kind of cloth shoes. 5. There will not be so much damage incurred by stretching and the possible consequence tearing and ripping of the material to make the upper lay straight on the last. 6. There will be no burning of the skin or other material because there are no wrinkles on which to use a gas, electrical, or other heated iron. 7. There will be no crooked sides, back or front during the time the shoe is being manu- 125

180

factured. 8. There will be a considerable saving, at least seventy-five per cent, in fixing and repairing when finishing the shoe.

A shoe made in accordance with my method of measurement will be comfortable to the wearer's foot. There will be nothing to hurt the foot because every part of the shoe will lay in its proper position. No part of the upper will force another part out of its place.

10 That part of the vamp which covers the big toe, at the beginning of the toe box will not press the foot and will not become creased and wrinkled as in the case of a shoe made on the equal style of measurement. Neither will 15 there be any wrinkles in the arch chamfers of the vamp at the inside or outside of the shoe.

The wearer will not be able to turn the shoe to the inside or the outside of the foot 20 so easily and therefore the shoe is more likely to remain straight.

The heel lining of the shoe, especially the low shoe will not wear out so quickly because the lining will remain stationary instead of 25 constantly moving as in the shoe made by the equal measurement method. The quarters around the ankles of the low shoe will not open during the act of walking but will remain snug about the foot of the wearer. Also 30 the sides of slippers near the vamp will not open during the act of walking but will fit closely to the foot.

The high shoes will not have abnormal wrinkles in the top quarters neither will the 35 boots have wrinkles on the leggings, because the quarters and the sides of the leggings will not pull each other.

To make the uppers by the equal measurement method, it costs from 15% to 25% of all 40 the work of turning out the finished shoe.

By the use of my method of measurement and cutting, it will take from one to three per cent more work in cutting and fitting the uppers but will require from twenty to thirty-five per cent less work in actually making, 45 finishing or assembling the parts of the shoe.

The results or advantages of my method of measuring and cutting shoe uppers are:—

1. Less trouble for the working man.
2. Less trouble for the manufacturer.
3. Less work required to produce the finished product.
4. Better looking shoes.
5. Greater comfort for the wearer.
6. Shoes having twenty-five to fifty per cent more wearing qualities.

Of course I do not wish to be limited to the exact details of construction as herein shown, as these may be varied within the limits of 50 the appended claims without departing from the spirit of my invention.

Having thus fully described my invention, what I claim as new and useful is:—

1. A shoe upper including a vamp in which, 55 when the upper is laid flat, the rear end of

the outside part is a greater distance from the front end of the vamp than the rear end of the inside part, lower quarters connected with the vamp, a line connecting the rear ends of said quarters from the inside portion of the upper to the outside portion thereof extending substantially at an angle to a perpendicular to the longitudinal medium line, with that point which becomes the lower rear corner of the inside quarter in the finished article of footwear being nearer to the front end of the vamp than that point which becomes the rear lower corner of the outside quarter, the point which becomes the upper rear corner of the inside quarter being positioned relative to the front end of the vamp, forwardly of the point which becomes the lower rear corner of the same quarter and the point which becomes the upper rear corner of the outside quarter being positioned, relative to the front end of the vamp, forwardly of the point which becomes the lower rear corner of the inside quarter and rearwardly of the points which become the upper rear corner of the inside quarter and the lower rear corner of the outside quarter.

2. The structure set forth in claim 1 in combination with top quarters having their lower edges fashioned to correspond with the contiguous edges of the vamp and lower quarters and the rear edge of the inner top quarter extending beyond the rear edge of the outer top quarter when super-imposed one on top of the other with their forward and upper edges coinciding.

3. A shoe upper including a vamp in which, when the upper is laid flat, the rear end of the outside part is a greater distance from the front end of the vamp than the rear end of the inside part, lower quarters connected with the vamp, a line connecting the rear ends of said quarters from the inside portion of the upper to the outside portion thereof, extending substantially at an angle to a perpendicular to the longitudinal medium line, with that point which becomes the lower rear corner of the inside quarter in the finished article of footwear being nearer to the front end of its vamp than that point which becomes the rear lower corner of the outside quarter, the point which becomes the upper rear corner of the inside quarter being positioned relative to the front end of the vamp, forwardly of the point which becomes the lower rear corner of the same quarter and the point which becomes the upper rear corner of the outside quarter being positioned, relative to the front end of the vamp, forwardly of the point which becomes the lower rear corner of the inside quarter and rearwardly of the points which become the upper rear corner of the inside quarter and the lower rear corner of the outside quarter, and leg elements having the lower edges fashioned to correspond to the contiguous edges of the
